UNITED STATES PATENT OFFICE.

LEWIS H. FALLEY, OF KANSAS CITY, MISSOURI

APPARATUS FOR DEWATERING AND SEPARATING ORES, SANDS, &c.

1,312,027.

Specification of Letters Patent.

Patented Aug. 5, 1919.

Application filed July 29, 1918. Serial No. 247,125.

To all whom it may concern:

Be it known that I, LEWIS H. FALLEY, a citizen of the United States, residing at Kansas City, in the county of Jackson, State of Missouri, have invented certain new and useful Improvements in Apparatus for Dewatering and Separating Ores, Sands, &c., of which the following is a full specification.

The present invention relates to devices for use in connection with ore concentrating mills, and aims to provide an improved apparatus for dewatering and separating ores, gravels, sands, etc., which comprise the mill run of dirt resulting from the operation of such mills.

Accordingly I have devised an apparatus to take the place of the usual form of dewatering screens, and operating to conduct the material in a more or less wavelike or zigzag path, and thereby agitating and loosening the mass of rock, ore, sand, gravel, etc., and separating the finer from the coarser particles, and from time to time removing the relatively finer particles along with a large percentage of the water from the main current of the material.

For accomplishing this result I provide a tank device through which the material is passed and its path interrupted and broken by a baffle structure for producing the desired character of flow, and the separated products are intermittently taken off by means of outlet passages and conduits and thereby removed from the rest of the material which is being carried through the tank.

It is also an object to devise an apparatus of the character described in which provision is made for controlling the separating action thereof by the use of closed conduit passages having means for regulating the degree of air pressure therein.

It is further sought to provide a simple and economical construction of this character which may be cheaply manufactured as well as installed and operated at a minimum of expense.

With these general objects in view, the invention will now be described in detail by reference to the accompanying drawings illustrating one form of construction which has been devised for embodying the improvements, after which the novel features

therein will be set forth and defined in the appended claims.

In the drawings—

Figure 1 is a vertical sectional elevation illustrating an apparatus constructed and arranged in accordance with the present invention;

Fig. 2 is a plan view of the same;

Figs. 3 and 4 are transverse sections taken on the lines 3—3 and 4—4, respectively, of Fig. 1, Fig. 4 being drawn to a larger scale;

Fig. 5 is a perspective view of a pair of the baffle members; and

Fig. 6 is a sectional detail illustrating the adjustable securing means for said baffle members.

Referring to the said drawings in detail, these illustrate a tank 8 having its upper end arranged in communication with a chute 10 for discharging the material to be treated into the tank. This tank is arranged at a greater or lesser angle to the horizontal, depending upon conditions as hereinafter explained, the drawings showing the same positioned at an angle less than vertical. Within the tank is provided a series of trough-like baffle members 12 and 14, the same projecting from opposite sides of the tank on a downward incline, with the lower ends of the members 12 intersecting the lower ends of the members 14. The lower end portions of the baffle members 14 are forked (see Fig. 5) for receiving the lower tapered ends of the members 12, which latter have the shouldered portions 16 spaced from the forked portions of the members 14 when the parts are arranged in proper relation; and in this position a space 18 is left open for the passage of the material between each pair of members 12 and 14. The upper ends of the members 12 and 14 are formed with flanges 20 having slots 22 for the use of bolts 24 in securing said members to the tank walls, this construction permitting adjustment of said members into their proper positions as shown in Fig. 5, and also for taking up any wear incident to the use of the apparatus.

Adjacent the upper end of each baffle member 12 is an outlet opening 26 provided in the corresponding wall of the tank 8, said opening being shielded by means of a hood

member 28 projecting from the inner face of said tank wall in position to overlie said opening 26. At the upper end of each baffle member 14 is provided a similar outlet 5 opening 30 through the opposite wall of the tank, and each member 14 carries a hood element 32 adapted to shield the corresponding opening 30 and form a restricted passage leading thereto.

10 The outlet openings 26 communicate with a closed conduit passage 34 formed by a conduit casing 36 on the outer face of the corresponding side of the tank 8. Separate conduit passages 34 are provided for each 15 set of a given number of said openings 26, the drawings showing a passage 34 for each set of three adjoining openings 26, and a discharge pipe 38, having a valve 40, leading off from each passage 34. An air vent 20 valve 42 is also provided for regulating the air pressure within the casing 36. The outlet openings 30 also communicate with similar closed passages 34 formed by a similar conduit casing 36 on the outer face of the 25 opposite side of the tank 8, from which passages discharge pipes 38 lead to any desired points, an air vent valve 42 being provided the same as for the other casing 36.

The side wall of the tank which carries 30 the baffle members 12 is made removable so that this whole side of the tank, with its baffle structure, may be readily taken out for inspection and repair whenever necessary, said tank wall being detachably secured by 35 bolts 44 to flanges 46 at the corners of the tank.

The lower end of the tank discharges into a hopper 48 having a discharge pipe 50 controlled by a valve 52. An overflow basin 54 40 is arranged in communication with the top of the hopper 48, and provided with an outlet pipe 56 with a valve 58, and also with a drain pipe 60 fitted with a valve 62.

In the operation of the apparatus, the 45 material comprising water, ore, sands, etc., is fed in a stream into the top of the tank, which of course becomes filled with the sludge water up to the level of the uppermost openings 26 and 30. In passing 50 through the tank, a wavelike motion is imparted to the water flow by the baffle structure above described, which breaks the downward course of the material, agitates it, and separates the finer particles from the coarser 55 and heavier,—the finer particles gradually leaving the tank by way of the outlet openings 26 and 30. The provision of the hoods overlying said openings serves to set up a suction or flow in the direction of the openings, which suction or flow takes up the lighter particles of ore and sands as branch currents are started through these several openings. The intersecting baffle structure, with the lower ends thereof terminating 60 opposite the outlet openings is such as to

concentrate the finer or lighter material more or less in the vicinity of the openings and thus subject said material more freely to the suction action of the various openings. As the flow continues through the 70 tank, practically all the water and finer particles of ore, sand, gravel, etc. are separated and drawn off through the several series of outlet openings, and the coarser material is left to be deposited in the hopper 48 with 75 but a small percentage of the water, the surplus water after leaving the tank being drawn off through the overflow basin 54. The separated material discharged through the various sets of outlet openings 26 and 80 30 is carried off by the conduits 38, one corresponding to each set of said openings, so that the grades of material of approximately the same size are thus taken up and collected at one point.

85 It is thus apparent that a simple and efficient improved apparatus has been devised for fulfilling the desired objects of the invention. The apparatus may be set at any desired angle to the horizontal; the greater 90 the angle the coarser the particles which will be separated, cleaned and dewatered. Where there is a large variance as to size of rock, sand, etc., the tank should be set perpendicular or nearly so, depending upon 95 the sizes to be separated out from the coarser particles; but where the mill dirt runs more uniform, the tank will be set at a greater slant than otherwise. The distance between the baffle members of course also depends 100 upon the coarseness or fineness of the mill crush to be treated.

The flow from the tank into the collecting conduits is conveniently and accurately regulated by increasing or diminishing the 105 quantity of air admitted through the valves 42 at the top of each conduit, as well as by means of the valves controlling the discharge from said conduits. By this regulation of the flow through the conduits, in 110 addition to the control afforded by the discharge valves 52 and 58, the amount of water drawn off from the main flow or current within the tank is also determined and controlled. With the arrangement and construction described, all use of screens is 115 eliminated, and no mechanical movement of any of the parts is employed; nevertheless the material being treated is kept constantly in motion and a continuous separating 120 action is maintained from start to finish; there is, moreover, no possibility of any packs or stoppage, there being no pockets of any kind where the material can accumulate and stop the downward flow. When the 125 baffle members become worn from use, it is obvious that the adjustable securing means provided enables said members to be reset to restore the original relative position of the parts.

While I have illustrated and described one suitable form of embodiment of the proposed improvements, I desire to reserve the right to make such modifications or changes as may fairly fall within the scope of the appended claims.

What I claim is:

1. An apparatus of the character described comprising a tank, a plurality of baffle members arranged at different elevations to impart a zigzag flow to the material passing through the tank, said tank being provided with an outlet opening for each of said baffle members, and a conduit communicating with a given number of said outlet openings for collecting and carrying away the discharge therefrom.
  2. An apparatus of the character described comprising a tank, a plurality of transverse baffle elements arranged at different elevations to impart a zigzag flow to the material passing through said tank, said tank being provided with an outlet opening for each of said baffle members, and a closed conduit communicating with a given number of said outlet openings for collecting and carrying the discharge therefrom.
  3. An apparatus of the character described comprising a tank, a plurality of transverse baffle elements arranged at different elevations to impart a zigzag flow to the material passing through said tank, said tank being provided with an outlet opening for each of said baffle members, a closed conduit communicating with a given number of said outlet openings for collecting and conducting the discharge therefrom, and means for controlling the air pressure within said conduit.
  4. An apparatus of the character described comprising a tank provided with a series of outlet openings at opposite sides thereof, a series of baffle members arranged to impart a zigzag flow to the material passing through the tank, said baffle members terminating in the vicinity of said outlet openings, and a conduit communicating with said openings for collecting and conducting the discharge therefrom.
  5. An apparatus of the character described comprising a tank, a plurality of oppositely arranged transverse baffle members located at different elevations to impart a zigzag flow to the material passing through
- the tank, said tank being provided with an 55 outlet opening at the upper end of each of said baffle members, and conduits at opposite sides of the tank, each communicating with a given number of said outlet openings for collecting and conducting the discharge 60 therefrom.
6. An apparatus of the character described comprising a tank, a plurality of transverse baffle members arranged at different elevations to impart a zigzag flow to 65 the material passing through the tank, said tank being provided with an outlet opening at the upper end of each of said baffle members and with a hood member overlying and guarding said opening, and a conduit member 70 communicating with said outlet openings for collecting and conducting the discharge therefrom.
7. An apparatus of the character described comprising a tank, a plurality of 75 transverse baffle members carried by the opposite side walls of the tank and located at different elevations and in alternating relation for imparting a zigzag flow to the material passing through the tank, and 80 means for removably securing one of said side walls to the remainder of the tank.
8. An apparatus of the character described comprising a tank, a plurality of intersecting baffle members arranged at different elevations to impart a zigzag flow to the material passing through the tank, said tank being provided with an outlet opening for each of said baffle members, and means 85 for securing said baffle members to the walls 90 of the tank, said means permitting adjustment of said baffle members relatively to each other.
9. An apparatus of the character described comprising a tank, a series of baffle 95 members arranged at different elevations within the tank for imparting a zigzag flow to the material passing therethrough, said tank being provided with an outlet opening for each of said baffle members, and a plurality 100 of conduit members communicating at different elevations with different sets of said outlet openings for collecting and conducting the discharge therefrom.

In witness whereof I hereto affix my signature

LEWIS H. FALLEY.
